UNITED STATES PATENT OFFICE.

WILLIAM L. BAKER, OF NEW ORLEANS, LOUISIANA.

OIL BURNER.

Application filed November 23, 1925. Serial No. 70,948.

The invention relates to improvements in burners in which fuel and air or possibly fuel and steam are atomized and mixed for thorough combustion, the fuel being preferably heavy oil.

In connection with burners of the type set forth, particularly those which operate on the mechanically atomizing principle of mixing oil and air, difficulty is encountered in producing a structure which will thoroughly atomize the oil and so mix it with the air as to form a homogeneous readily combustible mixture. It is the primary object of my invention therefore, to provide a new and improved structure wherein such difficulties as those previously encountered, are effectively overcome, the construction being such that the mixed fuel and air are discharged to form a hollow cone of the mixture, with the well-known advantages.

A further object of the invention is to provide an atomizing structure including a rotatable spinner at the burner tip, which is lubricated effectively by the fuel oil, the construction being also of a nature to keep the burner tip clean, insuring discharge of even the heaviest particles of the fuel.

A still further aim is to provide a burner which is of simple and inexpensive construction, yet will be highly efficient.

With the foregoing in view, the invention resides in the novel subject matter herein-after fully described and claimed, the description being supplemented by the accompanying drawing.

Fig. 1 is a vertical longitudinal sectional view partly in elevation, showing the application of my improvements to a burner of the general type disclosed in my United States Patent No. 1,524,964 of February 3, 1925.

Fig. 2 is an enlarged longitudinal sectional view through the construction at the tip of the burner.

Figs. 3 and 4 are vertical transverse sectional views as indicated by lines 3-3 and 4-4 of Fig. 2.

In the drawings above briefly described, the numeral 1 designates an outer tube having an open delivery end 2, said tube being adapted to conduct a fluid under pressure, preferably air. In the present showing, this tube is mounted and receives air in the same manner as disclosed in my prior patent, above referred to.

Disposed longitudinally in the tube 1 and

co-axially related therewith is a fuel conducting tube 3 of considerably smaller diameter than the outer tube. This tube 3, in the present showing, is mounted and receives oil under pressure in substantially the same manner as in the aforementioned patent. To retain the front end of the tube centered within the tube 1 however, a plurality of screws 4 or equivalent means, may be employed.

The delivery end of the tube 3 is disposed substantially at the delivery end 2 of the tube 1 and is formed with an internally beveled valve seat 5. This seat co-operates with a beveled valve 6 carried by the front end of an adjustable and operating stem 7 which is mounted and controlled in the same manner as in the patent previously mentioned. By properly manipulating the stem 7, the valve 6 may either be closed or may be opened to any desired extent, and when so opened, it delivers the fuel obliquely to the axis of the burner and in the form of a spray.

A sleeve 8 is rotatably mounted co-axially with the tubes 1 and 3, both ends of said sleeve being open. The inner end of the sleeve is positioned to receive fuel discharged between the seat 5 and the valve 6, the arrangement being such that this fuel will be directed obliquely against the inner side of said sleeve. Preferably, the inner end of the sleeve 8 surrounds the delivery end of the tube 3 and a sufficient space 9 exists between them, to allow a quantity of air from the tube 1, to enter the sleeve. This sleeve is rotatably mounted and provision is made for rapidly spinning it, and said tube preferably increases in diameter from its inner toward its outer end. By this formation, particles of oil which might otherwise cling to the interior of the sleeve, are acted upon by centrifugal force and are caused to travel toward the large end of the sleeve, for discharge with the other fuel.

In the preferred formation, a plurality of pitched webs 10 are provided on the inner side of the sleeve 8, said webs radiating from a hub 11 which is rotatably mounted on the valve 6, a shouldered screw 12 being preferably employed for so mounting said hub. Additional, pitched webs 13 are shown projecting outwardly from the sleeve 8 and terminating slight distances from the inner side of the tube 1, at the delivery end 2 of said tube. The air under pressure striking the webs 13 effects rotation of the sleeve.

8, so that the webs 10 will effectively atomize the oil and thoroughly mix it with the air entering through the space 9, and it will be understood that the oil under pressure, striking said webs 10, also assists in rotating the sleeve.

The invention has been constructed and used with exceptionally good results, and even when consuming very heavy grades of fuel oil, such oil is thoroughly atomized and mixed with the air under pressure entering through the space 9, the homogeneous mixture of air and fuel vapor being discharged in the form of a hollow cone. This mass of fuel is of course rapidly rotated due to the spinning action of the burner tip. The same is true of the air which discharges between the sleeve 8 and the tube 1, the result being that all of the violently whirling air and fuel vapor is most thoroughly intermingled, so as to produce a highly combustible mixture and consequently an exceptionally hot flame.

On account of the excellent results obtainable from the details disclosed, they are by preference followed. However, within the scope of the invention as claimed, various modifications may be made.

I claim:

1. An oil burner comprising a tube for conducting oil under pressure, said tube having an internally beveled delivery end, a beveled valve cooperable with said end, and means for moving said valve toward and from said end; a hub at the outer side of said valve and rotatably mounted on the latter, pitched webs radiating from said hub, and a sleeve surrounding and secured to said webs, said sleeve having open ends, one of which is disposed around said valve. 40

2. An oil burner comprising a tube for conducting oil under pressure, said tube having an internally beveled delivery end, a beveled valve cooperable with said end, and means for moving said valve toward and from said end; a hub at the outer side of said valve and rotatably mounted on the latter, pitched webs radiating from said hub, a sleeve surrounding and secured to said webs, said sleeve having open ends, one of which is disposed around said valve, additional webs radiating from said sleeve, and means for directing fluid under pressure against said additional webs. 45

In testimony whereof I have hereunto affixed my signature. 50

WILLIAM L. BAKER.
